GASKET DISPLAY RACK

William R. Anderson, Perrysburg, Ohio, assignor to Anderson Associates Inc., Toledo, Ohio, a corporation of Ohio

Application May 26, 1954, Serial No. 30,679

Term of patent 3½ years

(Cl. D80—9)

To all whom it may concern:

Be it known that I, William R. Anderson, a citizen of the United States, and resident of Perrysburg, in the county of Wood and State of Ohio, have invented a new, original, and ornamental Design for a Gasket Display Rack, of which the following is a specification, reference being had to the accompanying drawing, forming a part thereof.

In the drawing:

Fig. 1 is a front perspective view of a gasket display rack showing my new design;

Fig. 2 is a rear elevation of the display rack;

Fig. 3 is a top plan view; and

Fig. 4 is an end elevation taken from the left of Fig. 1.

I claim:

The ornamental design for a gasket display rack, substantially as shown.
